CLAIM

The ornamental design for a security label for an electronic device, as shown and described.

DESCRIPTION

FIG. 1 is a top view of a security label for an electronic device shown in a first state in a transition sequence, showing my new design; and,

FIG. 2 is a top view shown in an activated second state in a transition sequence.

The article in this patent includes a process or period in which the surface ornamentation changes into another surface ornamentation. The process or period in which the first state transitions into the second state forms no part of the claimed design.
